UNITED STATES PATENT OFFICE.

HUGO GILLER, OF NEW YORK, N. Y.

COIN-CONTROLLED CLOCK AND MONEY-BOX.

No. 812,200.

Specification of Letters Patent.

Patented Feb. 13, 1906.

Application filed November 7, 1904. Serial No. 231,656.

To all whom it may concern:

Be it known that I, HUGO GILLER, a citizen of the United States, residing in the borough of Brooklyn, of the city of New York, in the State of New York, have invented certain new and useful Improvements in Coin-Controlled Clocks and Money-Boxes, of which the following is a specification, reference being had to the accompanying drawings, forming a part hereof.

This invention relates to combined clocks and money-boxes or savings-banks, and has for its object to provide improved means for the control of the clock mechanism by the introduction of a coin, whereby the continued running of the clock is made to depend upon the deposit of a coin. In some other devices of this character it has been proposed to provide a stopping or braking mechanism whereby the clock-train shall be stopped at a predetermined time unless in the meantime a coin has been deposited for savings. Such an arrangement is unsatisfactory in that it requires the deposit of the coin before a certain hour each day unless the clock is to be permitted to stop and its accuracy and reliability as a timekeeper thereby destroyed. It is not always possible for an individual to deposit the necessary coin before a certain hour on every day of the week, and it therefore must happen frequently with the arrangements referred to that the clock is stopped and must be set again. It is more desirable to permit the clock to run until it has run down, if it so happens, and to make the rewinding of the clock dependent upon the deposit of the required coin. This not only permits more leeway in the time of depositing the coin, but the rewinding of the clock and the depositing of the coin being necessarily related act as a reminder each for the other, so that the habit of saving and the habit of rewinding the clock are both promoted, while the stopping of the clock and the destruction of its reliability as a time-keeper become less liable to happen by casual delay in the depositing of the coin.

It is the object of this invention, therefore, to provide an improved device of this charac-

ter in which the rewinding of the clock is dependent upon the deposit of the coin.

The invention will be more fully described hereinafter with reference to the accompanying drawings, in which a convenient and practical embodiment thereof is represented.

In the drawings, Figure 1 is a view in front elevation of a combined clock and money-box having the invention applied thereto. Fig. 2 is a side view of the same, partly broken out and in section, to show details of construction. Fig. 3 is a view in rear elevation with the back of the box removed, some parts being shown also in section and partly broken out. Fig. 4 is a partial view similar to Fig. 3, but showing the parts in a different position.

The clock mechanism may be of any usual or suitable character, and the case thereof, which also forms the money-box, may likewise have any desired shape.

As shown in the drawings, the clock mechanism, as represented at *a* by the face and hands thereof, is centrally located within the case *b*, which may have in its top *c* a slot *d* for the reception of the coin. Some portion of the casing may be provided with a door through which access may be had to the receptacle within to permit of removal of the deposited coins. As shown in Fig. 2, the entire back *e* of the casing is so arranged as to be removable, being provided at its lower end with lugs *e'*, which may enter slots in the bottom of the casing, and with a lock *e''* to engage the opposite end of the casing. There is also preferably arranged within the casing a partition *b'* *b''*, which forms a separate receptacle in which the coins which are deposited may be allowed to accumulate without liability of interfering with the clock mechanism, even if the clock should be overturned. The lower portion *b''* of the partition may be made removable to permit access to the interior of the casing beyond the coin-receptacle when necessary, and such removable partition *b''* may be provided with a flange *b'''* to cooperate with the back *e* for the purpose of cutting off the lower portion of the coin-receptacle, such flange having an opening *b''''* to per-

mit the passage of the coins from the coin-chute. The back may be apertured in line with the setting-arbor f and with the winding-arbor g to permit the introduction of the 5 setting-key f' and the winding-key g' .

The coin-operated devices, which permit or prevent the winding of the clock, are arranged to coöperate with the winding devices. In the present instance they are represented as coöperating directly with the winding-arbor g , which is provided, as shown in Figs. 3 and 4, with one or more stops or lugs or arms g^2 . Adjacent to the winding-arbor is mounted a stop-lever h , the same being conveniently pivoted upon the setting-arbor f . It is provided with a suitable shoulder h' for coöperation with the stops g^2 on the winding-arbor and is pressed normally toward the arbor, as by a spring h^1 , so that when the 15 stop-lever h is in normal position it is not possible to wind the clock. At the same time the stop-lever yields to permit the rotation of the winding-arbor in the opposite direction as the clock runs. The stop-lever is arranged 20 to be moved into abnormal position to permit the winding of the clock and is held in such position for a sufficient length of time to permit the rewinding of the clock. The means whereby it is moved to abnormal position and there held comprise an arm h^2 , arranged for coöperation with the coin, as herein-after described, and provided with a tooth h^3 for engagement with the corresponding tooth i of a latch i' . The latch i' is counter- 25 weighted or balanced, so that it stands normally in a position to engage the arm h^2 , and thereby to hold the stop-lever h in abnormal position. It is also arranged to be disengaged therefrom when the clock has run for a 30 short time. For this purpose there is pivoted upon the latch i' a dog k , having a toe k' for coöperation with the stops or lugs g^2 on the winding-arbor and coöperating with a stop k^2 on the latch. During the winding of 35 the clock the dog k swings freely on its pivot as the stops g^2 strike the toe k' ; but as the arbor rotates in the opposite direction the stop k^2 prevents the yielding of the dog k on the latch i' , so that the latter is swung upon its pivot and is made to release the stop-lever h . In this manner the parts are restored to their 40 locking position and the winding of the clock is prevented, except for a short time after the introduction of a coin.

55 The coin-chute l , which receives the coin through the slot d , is suitably formed to guide the coin into proximity to the arm h^2 of the stop-lever h and is cut away at its lower end, adjacent to the arm h^2 , to permit the latter 45 to project somewhat within the chute, as clearly indicated in Fig. 3, for the purpose of detaining the coin at this point until it has been made use of to effect the release of the

winding mechanism, a lug or shoulder l' being preferably provided at the opposite side of 50 the chute to coöperate with the arm h^2 . Adjacent to the lower end of the coin-chute there is mounted in suitable ways m a pusher having a stem n projected through the outer casing b . This pusher is preferably forked, as shown, having two arms n' , which straddle the stop l' and are suitably formed at their ends, as at n^2 , to engage the coin, as clearly shown in Fig. 4. A spring n^3 serves to draw back the pusher after operation. 55

It will now be understood that when a coin is introduced through the slot d it moves to the lower end of the coin-chute, where it is detained by the arm h^2 and the stop l' , these parts being then in the position represented in Fig. 3, in which position of the arm h^2 the stop-lever h is in engagement with the arms g^2 on the winding-arbor, so that winding of the clock is impossible. When the coin has 60 reached the position just described, the pusher n is thrust forward, engaging the coin and carrying it forward against the arm h^2 , whereby the latter is also moved forward and the stop-lever h^1 is moved out of engagement with the winding-arbor. If the pusher is now released, it returns to its normal position, and the coin drops into the receptacle below the end of the chute. The stop-lever, however, is held in its unlocking position through the engagement of the arm h^2 with the latch i' , so that it is possible to wind the clock. After a short time one of the lugs g^2 on the winding-arbor, acting through the dog k , swings the latch i' on its pivot, releasing the stop-lever h and permitting it to return to the locking position, which is represented in Fig. 3. It is thereafter impossible to rewind the clock until another coin is introduced. 65

Obviously various changes may be made in details of construction and arrangement of the mechanism, and it is to be understood that the invention is not restricted to the precise details of construction and arrangement herein shown and described. 70

I claim as my invention—

1. The combination with a clock mechanism, of a lug on the winding-arbor, a stop-lever normally engaging said lug, means to move the stop-lever into abnormal position, a latch to hold said stop-lever in abnormal position, and a dog pivoted on the latch in the path of said lug and free to move in one direction only, substantially as described. 75
2. The combination with a clock mechanism, of a lug on the winding-arbor, a stop-lever pivoted adjacent to said arbor and normally engaging the lug thereon to prevent the winding of the clock, means to disengage said stop-lever, and a latch to hold said stop-lever in abnormal position and pivoted ad- 80

ja~~c~~cent to the winding-arbor to be operated by the movement of the lug thereon to disengage said stop-lever, substantially as described.

5 3. The combination with a clock mechanism, of a lug on the winding-arbor, a stop-lever pivoted adjacent to said arbor to engage said lug, means to move the stop-lever into abnormal position, a latch to hold said stop-
10 lever in abnormal position and pivoted ad-

ja~~c~~cent to the arbor, and a dog pivoted on said latch in the path of said lug on the winding-arbor and free to move in one direction only, substantially as described.

This specification signed and witnessed 15
this 2d day of November, A. D. 1904.

HUGO GILLER.
